BENJAMIN S. BENSON, OF BALTIMORE, MARYLAND.

Letters Patent No. 71,687, dated December 3, 1867.

IMPROVEMENT IN CASTING METAL PIPE.

The Schedule referred to in these Letters Patent and making part of the same.

TO ALL WHOM IT MAY CONCERN:

Be it known that I, BENJAMIN S. BENSON, of Baltimore, in the county of Baltimore, and State of Maryland, have invented a new and useful Improvement in Casting Metallic Pipes; and I do hereby declare the following to be a full, clear, and exact description of the same, reference being had to the accompanying drawings forming part of this specification, and in which—

Figure 1 represents a detached view of the anchor used in casting and moulding pipes, which forms the subject of my improvement, and

Figure 2 is a view of the same when in position in the mould.

Similar letters of reference indicate corresponding parts in the several figures.

This invention consists in the use of an anchor, of improved form and construction, which does not scratch or wear the mould.

In casting or moulding metallic pipes of considerable length, it has always been very difficult to prevent the middle portion of the core from deflecting in some degree from a perfectly straight line, and thereby making one side of the pipe thicker and heavier than the opposite side. It is obvious that unless the walls of the pipe are of uniform thickness its usefulness for many purposes will be destroyed, and its durability will always be more or less impaired.

To compensate for such inequality in the thickness of the pipe, moulders have always been obliged to make the whole pipe thicker than would otherwise have been necessary, thereby consuming more material, and producing an article heavy and cumbersome for handling. To obviate this practical difficulty in the manufacture, I invented an anchor or stay for confining the core in the centre of the mould, upon which Letters Patent were granted to me, dated February 17, 1863, No. 37,670. It has been found, in the experience of several years' manufacture, that the device then patented sometimes scratches and injures the inner surface of the moulds. It is to obviate this difficulty, and perfect that device, that the invention has been made which forms the subject of this application, and which will now be more particularly described.

In the drawings, M M represent the walls of the mould, and C the core, in position for casting. A, fig. 2, indicates the anchor surrounding the core in the mould, and holding its external walls equidistant on all sides from the internal walls of the mould. The construction of this improved anchor is clearly shown in fig. 1, in which a indicates a hoop of wire, having its ends twisted or hooked together, and supporting three or more upright double plates, e e, of tin, tinned sheet iron, or other suitable metal, which are soldered or simply swaged to the wire, so as not to become detached from it. These plates are narrow, and about two inches in length, terminating at their upper extremity in slightly expanded disks, e' e'', parallel to and facing each other, one of the disks supporting a stout pin or bolt, i, which projects from it towards the other, the extremity of the bolt coming against the centre of the opposite disk when in position in the mould. The plates e e consist simply of a strip of tin of the required dimensions, doubled near its centre around the wire hoop, and having a half inch of the end to which the bolt is attached doubled inward for the bolt to pass through, the head of the bolt being held between the doubled parts, and the latter being firmly soldered or pressed together. The construction of these plates as thus described is shown clearly on the left side of fig. 1 of the drawings. The core rests against the inner disk e'', and is held in position by the bolts i i, which stand firmly between it and the walls of the mould. The bolts, however, do not touch the mould, as will be observed. No part of the instrument is designed to come in contact with the mould except the smooth outer surface of the outer plate e and its disk e', which entirely prevent the scratching or injuring of the mould while the instrument is being introduced.

Although this instrument is so simple and cheap that hundreds of them may be made by a boy in a day, at an expense of not more than a cent apiece, yet their use in the process of moulding pipes is of great importance, enabling pipes of the same thickness to be cast one-third longer than when they are not employed, and producing a better and more economical article of manufacture in every respect.

Having thus described my invention, what I claim as new, and desire to secure by Letters Patent, is—
The anchor or stay above described, consisting of the wire hoop a, the doubled plates e e, and the bolts i i, when the parts are constructed and arranged substantially in the manner shown, and for the purposes specified.
